CLAIM

The ornamental design for a hygrometer, as shown and described.

DESCRIPTION

FIG. 1 is a perspective view of a hygrometer show in a first configuration of use;

FIG. 2 is another perspective view of the hygrometer shown in the first configuration of use;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the hygrometer where a back cover is in a separation state;

FIG. 10 is a perspective view of the hygrometer shown in a second configuration of use;

FIG. 11 is a perspective view of the hygrometer shown in a third configuration of use; and,

FIG. 12 is a perspective view of the hygrometer shown in a fourth configuration of use.

The broken lines in the drawings depict portions of the hygrometer that form no part of the claimed design.
